UNITED STATES PATENT OFFICE.

CHARLES W. BALLMAN, OF INDIANAPOLIS, INDIANA.

BRUSH CLEANER.

Application filed November 17, 1923. Serial No. 675,351.

To all whom it may concern:

Be it known that I, CHARLES W. BALLMAN, a citizen of the United States, and a resident of Indianapolis, county of Marion and State of Indiana, have invented a certain new and useful Brush Cleaner; and I do hereby declare that the following is a full, clear, and exact description thereof, reference being had to the accompanying drawings, in which like numerals refer to like parts.

This invention relates to a device for cleaning brushes and the like, and is particularly adapted to clean flat brushes.

The chief object of the invention is to provide a cleaner for brushes which will clean sour or lousy brushes within the capacity of the device and clean said brushes from the bristle ends to substantially the heel thereof.

The chief feature of the invention consists in providing a pair of brushes each having one or more flat blades and which rotate oppositely, so that the bristles of one brush blade, while rotating, will work well within the path of travel of the bristles of another blade of the adjacent brush, whereby the brush to be cleaned will be alternately and oppositely engaged by the bristles of the adjoining brushes which pass from the heel to the bristle ends and which by reason of the present construction enters the brush to be cleaned with a slapping or whipping action, whereby the bristles of the cleaning brush are forced into the brush to be cleaned adjacent the heel thereof and substantially through the same, and then are passed downwardly through the brush to be cleaned to separate, straighten and clean the bristles thereof.

Another feature of the invention consists in providing a reservoir through which the brush blades pass for conveying cleansing fluid if desired, and this is true for hard brushes, to the bristles of the brush to be cleaned where the fluid passes downwardly along said bristles and through the same to increase the rapidity with which the bristles of the brush to be cleaned can be separated and cleaned. The fluid discharging from the brush to be cleaned and carried therefrom and therethrough by the bristles of the cleaning brush is discharged or returned to the reservoir with the paint particles, whereupon the paint particles settle in the bottom of

the reservoir and may be reclaimed for priming purposes. It is to be understood that it is not necessary to utilize a cleansing fluid if brushes are cleaned immediately following use, but best results are obtained from the additional use of a cleansing fluid in the reservoir.

Another feature of the invention consists in the construction of the device whereby the brush to be cleaned may be positioned and supported by a portion of the device in a predetermined relation with respect to the cleaning brushes, whereby the operator is not required to devote his entire attention to holding and positioning the brush to be cleaned, but is enabled to devote a portion of his attention to operating the device, as well as holding the same from slipping, at the same time holding the brush in position to be cleaned.

Another feature of the invention consists in the several structural details, whereby the parts are readily assembled; and when assembled, form a splash-proof construction.

Other features of the invention will be more specifically pointed out hereinafter.

The full nature of the invention will be understood from the accompanying drawings and the following description and claims:

In the drawings, Fig. 1 is a perspective view of the brush cleaning device embodying the invention, showing a brush to be cleaned positioned therein. Fig. 2 is a top plan view of the invention. Fig. 3 is a side elevational view thereof. Fig. 4 is a longitudinal sectional view of the invention with the brush to be cleaned shown dotted therein. Fig. 5 is a transverse sectional view of the invention. Fig. 6 is a diagrammatic view of a pair of modified cleaning brushes, showing the relationship therebetween. Fig. 7 is a similar view of another modified form of cleaning brushes.

In the drawings 10 indicates a reservoir or chamber having an inturned upper edge 11 which has a parallel portion 12 peripherally defining said reservoir. Said parallel flange 12 is inturned at 13 to form a rest or supporting ledge. The flange or ledge construction constitutes a splash-proof joint with the cover 14. The cover 14 herein is shown provided with two pairs of aligned openings 15 and 115. In one pair of openings, upon one side, there is seated by press

fitting or the like a shaft bearing 16 having a shaft-receiving opening 17 therein. A brush supporting shaft 18 has an elongated portion at one end. Due to the resiliency of the sides of the cover 14, said elongated end of the brush supporting shaft, after being positioned diagonally in the opening 115 opposite the shaft bearing supplied opening 15, has its other end seated in the shaft bearing opening 17 by springing outwardly the sides 14 of the cover a sufficient distance to permit said end to be seated in the bearing. Each shaft extension projecting through the opening 115 in the cover 14 carries a pin or key 19 seatable in a slot 20 formed in a gear 21. The gears 21 mesh with each other and thus the shafts 18 have opposite directions of rotation. A gear guard or gear housing includes a dished cover plate 22, which herein is shown positioned upon the exterior of the cover plate and the reservoir 10, and not only incloses said gears but depends from the cover 14 and lies parallel to the reservoir 10. Herein in the gear housing 22 is suitably secured to the cover 14, as by means of the bolts 23 and the nuts 24, although other suitable means may be provided. The cover 22 supports a pair of shaft bearings 25 and 26. The shaft bearing 25 has a closed end; while the shaft bearing 26 is not so formed. Extending through the shaft bearing 26 and projecting beyond the same, is the extended portion of one of the shafts 18; and suitably supported by said extended free end of the shaft 18 is a crank arm 27 having a handle 28. Actuation of the crank handle serves to rotate both shafts 18 in opposite directions, and, of course, in timed relation with each other.

The means for detachably securing the cover to the reservoir in the present instance includes an opening 29 formed in the side of the reservoir 10, and said opening is adapted to receive a pin 30 having a head 31, which pin head is positioned between the side of the reservoir 10 and the inner flange 12, thus securing said pin so that the same projects laterally from, and herein outwardly from the reservoir 10. Suitably secured upon the cover 14 is a yielding clip 32, as by means of the rivets 33, which clip is provided with a pin-receiving opening 34 to receive the pin 30. With this detachable connection, it will be understood the cover may be readily detached from and attached to the reservoir 10, to permit replenishing of the fluid in the reservoir 10, or permit cleaning of said reservoir; or to permit access to the brushes supported by the shafts 18.

The top of the cover 14 is shown provided with a depressed seat 35 having the side walls 36, and said side walls 36 are centrally apertured to receive the ends 37 of a bail

38 provided with an offset handle 39. This bail construction permits the cleaner to be transported by carrying, inasmuch as the device does not exceed twenty pounds and can be reduced to materially less than this weight. The foregoing construction also permits the bail to lie in the non-transporting position, as shown in Figs. 2 and 3, and provide a relatively clear access to an elongated opening 40 provided in the depressed seat 35, which elongated opening 40 lies parallel to and in spaced relation with the brush supporting shafts 18. Fig. 1 illustrates the arrangement whereby a brush is received by said elongated openings 40 for cleaning purposes without interference from the bail. Fig. 1 likewise illustrates the arrangement whereby the operator can hold the brush handle with one hand, resting the bristle retaining means on the seat 35 with the bristles projecting through the opening 40 and into the cleaner, and at the same time hold the entire brush cleaner from movement while actuating the cleaning brushes from without the cleaner with the other hand, by manipulating the crank handle.

Herein each of the shafts 18 is shown supporting a brush base 41 of any desired form, which is suitably secured to said shaft 18 as by the cotter pin 42, the shaft and base being provided with registering apertures for this purpose. Interposed between each brush base 41 and the adjacent side wall of the cover 14 not provided with the shaft receiving bushing 16, there is positioned a washer 43 which is of felt. This relatively leak-proof joint between the shaft 18 and the opening 115 of the cover 14 prevents the paint materials from splashing into the gear housing and gumming the gear teeth.

Herein, see Figs. 4 and 5, the preferred form of brush is illustrated, and the same constitutes a flat bladed brush, and in the present form of the invention each brush includes a pair of blades 44, which blades are formed in any suitable manner; and that at present utilized consists in stapling substantially U-shaped brush bristles to and seating the same in the brush base 41. These bristles preferably are of steel wire having considerable resiliency, but in mass formation being relatively stiff. Herein each brush is shown provided with a pair of oppositely positioned blades 44, although as shown in Figs. 6 and 7, said blades need not necessarily be oppositely positioned, but may be positioned in spaced relation about the shaft 18, as may be found desirable. However, see Figs. 4, 6 and 7, the brush blades are so positioned upon the shafts 18 that said brush blades have a common path between their axes and beneath the opening 40 in the cover 14. It will be noted that the bristles of one brush blade

while rotating, will travel well within the path of the bristles of another brush blade of the adjacent brush. Thus, one brush blade follows the brush blade of the other brush through the common path. The brush blades, therefore, alternately engage the bristles of the brush to be cleaned positioned in the opening 40 and from opposite sides and pass through said brush as shown clearly in Fig. 4. The depressed seat 35 adjoining and defining the opening 40 is so formed that it constitutes an abutment projected into the path of the bristles constituting the brush blade. As shown clearly in Fig. 4, the brush blade engages said abutment and the ends of the bristles are momentarily retarded until the retardation or bending is sufficient to permit said bristles to escape from said abutment and resume rotation with the remainder of the brush. Upon the escape from the abutment, said bristle ends move rapidly to catch up with the remainder of the brush; or in other words, resume normal radial position; and in so doing engage the bristles of the brush to be cleaned with a slapping or whipping action, thereby tearing into the brush and separating clean bristles from each other. Should the heel of the brush be so hard as to defy separation for some time, the same will constitute a continuation of the abutment 35 and the cleaning blades will gradually work their way deeper into the brush heel, so that after turning the crank several times, the cleaning bristles will pass substantially through the brush to be cleaned and also substantially from the heel to the end thereof. The travel of the blades through the liquid in the reservoir 10 serves to transport a portion of the liquid to the brush to be cleaned, and thus not only softens the paint, binding the bristles together, but serves to wash the loosened paint particles from the bristles of the cleaning brushes and the brush to be cleaned and discharge the paint into the reservoir.

In Figs. 6 and 7 there is shown a modified form of the invention, wherein the flat blades of the brushes are positioned in spaced relation with each other about the brush supporting shaft and in spaced relation to the blades of the other brush. In Fig. 6 the blades are positioned at 120 degrees apart with the blades of the adjacent brushes substantially 60 degrees apart. In Fig. 4 the blades of the brushes are substantially 180 degrees apart and are positioned 90 degrees apart with respect to the adjacent brushes. In Fig. 7 the blades are positioned in spaced relation with each other about the brush shaft and at 90 degrees apart; and the blades of the adjacent brushes are positioned substantially at 45 degrees apart. While an increase in the

number of brushes may be made, it is not believed that any increased utility will be derived from increasing the number of blades beyond four to the brush, for in such an event, the question of interference between the blades of adjoining brushes becomes a determining factor, especially in view of the whipping action secured as before described. Another determining factor is the difficulty of inserting the brush to be cleaned between the adjacent brush blades when a large number of blades per brush is employed.

The invention claimed is:

1. In a brush cleaner, the combination of a reservoir, a detachable cover therefor having a brush receiving slot therein, and means supported by the cover and movable into the reservoir when actuated for cleaning brushes inserted into said slot. 80

2. In a brush cleaner, the combination of a reservoir, a detachable cover therefor having a brush receiving slot therein, a parallel pair of substantially flat bladed brushes rotatably supported within and by said cover parallel to said slot and having a common path beneath said slot and movable into said reservoir when actuated for cleaning brushes inserted into said slot. 85

3. In a brush cleaner, the combination of a reservoir, a detachable cover therefor having a brush receiving slot therein, a parallel pair of substantially flat bladed brushes rotatably supported within and by said cover parallel to said slot and having a common path beneath said slot, a pair of meshing gears positioned at one side of said brushes for actuating the same, and a gear housing carried by the cover and projecting beyond the same to lie adjacent the reservoir. 100

4. In a portable brush cleaner, the combination of a reservoir, a detachable cover therefor having a depressed seat with a brush-receiving opening therein, and a bail carried by said cover for transporting the same and said reservoir. 110

5. In a brush cleaner, the combination of a pair of substantially flat bladed brushes mounted in parallel and in spaced relation for having a common path, and means positioned at each side of said path engageable by each brush blade when moving into the common path for momentarily retarding the movement of the blade end of the engaging brush. 115

6. In a brush cleaner, the combination of a brush supporting plate having a depressed brush receiving seat with an opening therein, and a pair of substantially flat bladed brushes mounted oppositely from said seat and in parallel with each other and the opening and in spaced relation therewith and each other for having a common path, said brush blades engaging the opposite face 125

of said depressed seat when moving into the common path for momentarily retarding the engaging end of the engaging brush.

6. 7. In a brush cleaner, the combination of a reservoir, a cover therefor, and detachably connected thereto to form a housing, brush cleaning means within the housing and movable through the reservoir when
10 actuating for cleaning purposes, and a splash-proof joint between said reservoir and cover.

8. In a brush cleaner, the combination of a reservoir, a cover therefor and detachably connected together to form a housing, brush 15 cleaning means within the housing and movable through the reservoir, and a laterally extending ledge upon said reservoir for supporting said cover and forming a splash-proof joint therebetween. 20

In witness whereof, I have hereunto affixed my signature.

CHARLES W. BALLMAN.
